UNITED STATES PATENT OFFICE.

WILLIAM H. VOSS, OF DAVENPORT, IOWA.

ATTACHMENT FOR WASHING-MACHINES.

Specification of Letters Patent. Patented Nov. 19, 1918.

1,285,485.

Application filed January 18, 1915. Serial No. 2,811.

To all whom it may concern:

Be it known that I, WILLIAM H. Voss, a citizen of the United States, residing at Davenport, in the county of Scott, State of Iowa, have invented a new and useful Improvement in Attachments for Washing-Machines, of which the following is a specification.

This invention relates to attachment for washing machines, and more particularly to a bench adapted to be applied to any washing machine or wash tub to support a plurality of auxiliary tubs used in the washing operation.

It is an object of this invention to provide a bench of the class described adjustable toward and away from the wash tub so as to accommodate different sizes of auxiliary tubs.

It is another object of my invention to provide a removable bench of the class described, of simple and economical construction, easy to be attached and removed from any tub.

It is another object of my invention to provide a bench of the class described where in a plurality of tubs may be used and brought successively into position adjacent the main tub.

It is another object of my invention to provide a bench of the kind described which may be folded up against the wash tub in such a fashion as to require no appreciable extra room for storage.

Other objects and advantages of the invention will appear as the description to follow proceeds.

In the drawings Figure 1 is an elevation of my tub and bench combined.

Fig. 2 is a plan view thereof partly in section.

Fig. 3 is a cross sectional view of the attachment on the line 3-3 of Fig. 2.

Fig. 4 is an elevation showing the bench folded up against the side of the tub.

Fig. 5 is a cross sectional view through the center of the bench on the line 5-5 of Fig. 2.

In the drawings 1 represents a washing machine tub provided as is customary with the legs 2. Upon two adjacent legs 2 and at the same height, are secured brackets 3 having bearing pins 4 thereon. Mounted upon the bearing pins 4 of the brackets 3

are links 5. The outer ends of the bearing pins are threaded and nuts 6 with washers are provided for securing the links to the brackets.

The bench proper comprises side members 7 connected by an end member 8 and having the legs 9 pivoted therein at 10 and provided with a cross piece 11 which takes against the bottoms of the side members 7 when the bench is in operation and prevents the collapse thereof, as clearly shown in Fig. 3. The legs 9 may also when desired be swung into folded position beneath the bench, the links 5 lowered to or near their lowermost position, and the outer end of the bench lowered until the cross piece 11 rests upon the floor, thereby permitting the bench to assume a substantially horizontal position, but at a lower elevation than that shown in Fig. 3. The sides 7 are spaced by a piece of tubing such as gas pipe 12 which fits between the upper ends of the links 5. A rod 13 is passed through the pipe 12, is threaded on either end and provided at either end with the thumb screws 14 with or without washers.

By the construction so far described, it will be apparent that the entire bench may be pulled away from or moved toward the washing machine for a considerable distance, the links 5 swinging on the brackets 3, and that when adjusted in the correct position, the bench may be firmly held against longitudinal shifting by tightening up the thumb screws 14 and the nuts 6, or the thumb screws 14 alone.

The side members 7 of the bench are provided with a platform made up of cross pieces such as indicated at 16. The central cross piece 16 is provided with a metallic plate 17 upon its lower surface and with a corresponding metallic bearing plate 18 upon its upper surface.

These two plates and member 16 therebetween are provided with a vertical aperture to receive the pivot pin 19 integral with the metallic boss 20 which is secured by means of bolts as shown to the under surface of the central cross piece 21 of the turntable 22. The turntable 22 is preferably made with channel iron sides 23 connected by wooden slats 24. Secured to the under side of the turntable are a number (in this instance 4) of rollers 26. Secured to the cross

pieces 16 of the bench is a corresponding circular track 27 upon which the rollers 26 move as the turntable 22 is revolved about the pivot 19.

5 The turntable 22 is here illustrated as of a size sufficient to carry two wash tubs as 28 and 29, although four or any other number could obviously be provided for, if desired, by simply making the turntable of the 10 requisite size.

In operation, the tubs 28 and 29 may be successively swung into position immediately adjacent the tub 1 of the washing machine. By means of the adjustable links 5 15 as heretofore pointed out, the entire bench may be moved toward or away from the washing machine sufficiently to permit the same bench to be used with washing machines of any diameter and to permit tubs 20 of the usual sizes to be used upon the turntable. When the washing machine is not in use, the device may be folded up against its side in such a fashion as to require no appreciable extra room for storage. This may 25 be done by dropping the links 5 as shown in Fig. 4 and then folding up the bench until it rests compactly against the side of the tub, the legs 9 folding down inside the frame of the bench as clearly shown.

30 I claim:
1. In apparatus of the class described, a support having vertically disposed members in spaced apart relation, a bench, a turntable on said bench, links connecting one end 35 of the bench to and supporting the same

Copies of this patent may be obtained for five cents each, by addressing the "Commissioner of Patents, Washington, D. C."

from the support, said links being pivotally connected to the support.

2. In apparatus of the class described, a support having a pair of brackets thereon, a pair of links pivoted on said brackets, a 40 bench comprising a pair of side pieces, means for adjustably connecting said links with said side pieces.

3. In laundry apparatus, supporting means adapted to be pivotally connected to 45 a tub support, a bench pivotally connected at one end to said supporting means and means for rendering one of said pivotal connections rigid.

4. In laundry apparatus a tub support, a 50 link pivotally connected to said support, a bench pivotally connected at one end to said link, means for rendering one of said pivotal connections rigid, said bench having at its opposite end a leg pivotally connected 55 thereto whereby when said link is secured at or near its uppermost position said leg may be swung down to support the bench and when said link is secured at or near its lowermost position said leg may be folded under said bench to permit said bench to occupy a substantially horizontal position.

In witness whereof, I hereunto subscribe my name to this specification in the presence of two witnesses.

WILLIAM H. VOSS.
